UNITED STATES PATENT OFFICE.

EDWIN V. BLANKENSHIP, OF BOZEMAN, MONTANA.

WATERING SYSTEM.

Application filed October 1, 1921. Serial No. 504,581.

This invention relates to irrigating systems, and more particularly to a novel system for conserving the water of mountain streams or the like for irrigating purposes.

5 The primary object of the invention is to provide means for directing the water from the mountain streams to convenient places to form glacial deposits, then to a reservoir or reserve tank, when practical and so desired novel means being provided to cause the water to freeze, prior to its entrance to the reservoir or tank.

10 With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed, may be made within the scope of what is claimed, without departing from the spirit of the invention.

Referring to the drawings:

Figure 1 is a view disclosing the manner 25 of directing water from mountain streams to reservoirs or the like and disclosing a composite winter and summer scene.

Figure 2 is a view disclosing means for utilizing the force of the fluid passing to the 30 reservoirs for operating a water wheel for generating power and disclosing a composite winter and summer scene.

Figure 3 is an elevational view of a pipe, one end thereof being shown in section to 35 illustrate the nozzle employed for breaking up the water passing from the pipe.

Figure 4 is an end elevational view of the same.

Referring to the drawings in detail, the 40 system is illustrated as embodying pipes 5 which may have one of their respective ends positioned to receive water from a stream or the like, it being understood that the stream should be an elevated stream so that 45 the water may gravitate through the pipe where the same may be deposited in a suitable reservoir or the like.

As shown by Figure 3 of the drawings, each of the pipes is provided with a head 6, 50 which head has a restricted portion 7 by

means of which the head may be secured to the pipe associated therewith. The pipes are provided with tapered extremities 8 forming integral nozzles which direct the water to the discharge end of the head 6. A flange 9 55 is formed within the head 6, which flange forms an abutment and contacts with the screening member 10 which may be formed of fine wire mesh material.

Positioned within one end of the head, is 60 a securing ring 11 which contacts with the screen 10 and forces the screen into engagement with the flange 9 to secure the same within the head.

From the foregoing it will be seen that as 65 water passes through the pipes, the same is discharged onto the screening member 10 where the water is broken into fine particles. It follows that the fine particles or spray fall into the reservoir, the spray is frozen 70 and deposited in the form of snow or ice.

In the form of snow or ice, the water is thus retained within the reservoirs until the warm weather causes the same to melt and flow through the various irrigating ditches 75 which are in communication with the reservoirs.

As clearly shown by Figure 2 of the drawings, a pipe 20 is shown as directing the water from a mountain lake to a reservoir, the reservoir being indicated at 21. This pipe 20 is provided with an enlarged portion 22 disposed between the ends thereof, and in which is positioned a water wheel 23 that is revolved by the water passing through the pipe 20 which impinges on the blades of the wheel. A suitable shaft may have connection with the wheel to carry off the power thus generated for operating suitable machinery, not shown. 85 90

It might be further stated that due to a conserving system as described, the water of the mountain streams which usually is wasted, during the winter months, over the sides of mountains, into creeks, rivers thence 85 into the ocean, may be directed to suitable reservoirs and retained therein in a frozen state, where the same will be caused to melt, due to the summer heat.

It follows that the water may now be di- 100

rected to suitable irrigating ditches, leading to agricultural and stock farms for the purpose of irrigating same.

Having thus described the invention, what is claimed as new is:—

A system of conserving water in elevated streams, consisting in conveying water from the elevated streams to an elevated point, breaking the water into a fine spray dis-

charging the spray into a cold atmosphere to cause a rapid freezing of the spray, and the final disposition of the same into a reservoir.

In testimony that I claim the foregoing as my own, I have hereto affixed my signature.

EDWIN V. BLANKENSHIP.
